SHOE CHANNELING AND GROOVING MACHINE

Gedeon Gregoire, Southbridge, Mass.

Application June 26, 1931, Serial No. 547,027

14 Claims. (Cl. 12—27)

This invention relates to improvements in sole channeling and grooving machinery and has particular reference to improved means and method of forming the said channel and groove.

The principal object of the invention is to provide improved means and method of simultaneously or independently forming a channel and groove in the sole of a shoe after the said sole has been fitted to the shoe and without removing the said sole from its fitted position on the shoe.

Another object of the invention is to provide improved means wherein the lip portion lifted from the channel will be automatically turned outwardly of the channel during the channeling and grooving operation.

Another object of the invention is to provide an improved cutter for simultaneously forming a channel and groove in the sole of a shoe.

Another object of the invention is to provide improved means for supporting the channeling and grooving cutter so that the said cutter will be relieved from abnormal strains and also to permit it to be self-feeding to a pre-determined depth during the channeling and grooving operation.

Another object of the invention is to provide improved feed and cutter means which are so related with each other that the channeling and grooving cuts will be formed at a point adjacent the vertical center line of the feed means.

Another object of the invention is to provide improved means for controlling the position of the channeling and grooving cuts with respect to the peripheral edge of the sole.

Another object of the invention is to provide improved means for controlling the depth of the channeling and grooving cuts.

Another object of the invention is to provide improved means for regulating the pressure of the feed means upon the sole of the shoe during the channeling and grooving operation.

Another object of the invention is to provide improved means and method of securing the sole to a shoe wherein the sole is sewed in position on the shoe.

Another object of the invention is to provide improved means for concealing the stitches in the sole portion of the shoe after the said sole has been sewed in position on the shoe.

Another object of the invention is to provide improved means and method of concealing the stitches in the sole portion of the shoe and for preventing the concealing means from being displaced during the use of the shoe.

Another object of the invention is to provide

an improved method of forming a sole channeling and grooving tool.

A further object of the invention is to provide an improved means and method of feeding the sole portion of the shoe into the channeling and grooving tool.

A further object of the invention is to provide an adjustable rotary table member for supporting the sole during the channeling and grooving operation.

A further object of the invention is to provide improved means wherein the channeling and grooving tool or cutter may be quickly interchanged and replaced.

A further object of the invention is to provide means wherein the channeling and grooving operations may be formed separately and independently of each other.

A still further object of the invention is to provide a sole channeling and grooving machine which may be adjusted to a position wherein only a channel is formed in the sole portion of the shoe, or only a groove portion is formed in the sole of the shoe, and to a position wherein the channeling and grooving operations are performed simultaneously.

A still further object of the invention is to provide improved means and method of forming a channel and groove in the sole portion of a shoe when it is in fitted position on the shoe or prior to its being secured in position on the shoe.

Other objects and advantages of the invention will become apparent from the following description taken in connection with the accompanying drawings and it will be apparent that many changes may be made in the details of construction, arrangement of parts and methods shown and described without departing from the spirit of the invention as expressed in the accompanying claims. I, therefore, do not wish to be limited to the exact details of construction, arrangement of parts and methods shown and described, as the preferred forms only have been shown by way of illustration.

The usual practice in preparing the sole portion of a shoe to be sewed in position on the shoe has in the past been as follows:

The sole was first secured to the shoe and cut to the contour shape thereof. The sole was then removed and a channel was formed therein at the contour edge of the shoe, and in most instances in the past, was formed by a hand tool designed particularly for this work. The sole was then re-fitted to the shoe and secured in place thereon so that it could be permanently sewed

to the shoe in this position. The stitches were formed in the channel and were thence concealed therein by cementing the lip portion of the channel thereover. In most instances in the past this channel portion extended to the extreme peripheral edge of the sole. The undesired feature of this type of channel was that the lip portion had a tendency to work loose during the use of the shoe and curl outwardly leaving the stitches exposed.

In the past, most sewing machines formed the large or knotted portion of the stitches internally of the sole. This type of stitching only required a slight channel in which the exposed portion of the stitches could be concealed, but with the present type of sewing machines the large or knotted portion of the stitches are formed on the exposed side of the sole. This type of stitching is believed to be more durable and efficient but is more difficult to conceal. The channel previously used was impractical, that is, after the sole had been sewed in position on the shoe, the lip portion could not be cemented back in its normal position in the channel. The exposed portion of the stitches would cause the lip to bulge in the vicinity thereof and cause the said lip to wear away quickly at this point and would also normally tend to cause the lip to be urged outwardly of the channel. It is quite apparent that with this method of concealing the stitches within the sole of the shoe, when the sole became dampened the lip portion would easily become dislodged from the channel and would curl outwardly at its free edge. This was due mostly to the fact that the lip portion could not be secured in its normal position within the channel and that the free edge of the lip portion extended to the extreme peripheral edge of the sole. Attention is directed to the fact that with most prior art devices the channeling operation could not be performed when the sole was in fitted position on the shoe, that is, the sole had to be removed from the shoe after it had been fitted thereto thence channeled and thence re-fitted to the shoe and secured in position thereon. Most prior art devices were manually operated and depended upon the skill of the operator and for this reason accurate results could not be obtained. They not only required a great deal of time but also caused a great wastage of material and did not produce satisfactory results.

To overcome the above defects the channel in this instance is not formed at the extreme peripheral edge of the sole portion of the shoe. A reinforcing space is left between the channel and the peripheral edge of the shoe so that the lip portion of the channel cannot be raised during the use of the shoe by stubbing the toe, etc.

Another feature of the present invention is that a groove is formed in the bottom of the channel. This groove is formed to receive the large or knotted portion of the stitches which, with the present type of sewing machines, is formed on the exposed side of the sole. This groove permits the lip portion to be secured in its normal position within the channel. This also obviates the tendency of the stitches to form a raised portion in the vicinity thereof after the said lip portion is secured within the channel. Attention is directed to the fact that this type of channel and groove permits the use of any type of stitching.

Another feature of the present invention is that this channel and groove can be formed simultaneously and to a predetermined depth and at a given distance from the peripheral edge of the

sole. The depth of the channel and groove and the position thereof with respect to the peripheral edge of the sole can be maintained throughout the forming of said channel and groove and will be uniform. The present method permits the forming of the channel and groove in the sole after it has been fitted to the shoe and does not necessitate the removing of said sole from its fitted position on the shoe. This improved means and method of forming the channel and groove and of securing the sole to the shoe does not only save much time but also prevents a great amount of wastage in material which has been usual with most prior art devices. Most prior art channeling devices depended solely on the skill of the operator and for this reason much difficulty was encountered in forming a uniform channel.

Another feature of the present invention is that the channeling and grooving operations can be performed simultaneously and with extreme accuracy, and can be performed on any contour shape of sole without removing the said sole from its fitted position on the shoe.

This improved means and method of preparing a sole and of securing the sole on a shoe is designed particularly for use in shoe repair work and is accomplished in an extremely simple and efficient manner. The new sole is first secured in position on the shoe, is then cut to the contour shape of the shoe, is then placed in the device embodying the invention and is channeled and grooved, the lip portion of the groove being simultaneously turned outwardly of the channel. It is then sewed in position on the shoe by a stitching within the groove, and the lip portion is then cemented in its normal position within the channel. This provides a very neat and durable construction.

Fig. XX is a view similar to Fig. XIX showing the forming of the channel independently of the groove.

Referring more particularly to the drawings wherein like characters of reference designate like parts throughout, the device embodying the invention comprises a main casting having a hollow base portion 1 and an intermediate U shaped portion 2 thereon. The U shaped portion 2 terminates in a transverse bearing 3 having a projecting arm 4 thereon. The arm 4 is provided with a vertical bearing 5 in which is slidably mounted the channeling and grooving tool 6. The said channeling and grooving tool is attached to the slide support by means of a lock screw 7 and is urged longitudinally of the bearing 5 by a spring member 8. The channeling and grooving tool 6 as shown in Figs. VI to VIII inclusive is formed with the cutting edge 9 which is adapted to form the channel 10 and the depending arcuate shape cutting edge 11 which is adapted to simultaneously form the groove 12 in the sole of the shoe. The cutting tool 6 is positioned adjacent a toothed edge feed roll 13 which is secured to a shaft 14 mounted in the bearing 3. The said toothed wheel is rotated by a handwheel 15 secured adjacent the opposite end of the shaft 14 and is adapted to feed the sole of the shoe into the channeling and grooving tool 6 during the channeling and grooving operation. A grooved disc 16 is mounted on the shaft 14 adjacent the toothed wheel 13 and is adapted to receive the lip 17 which is turned outwardly during the channeling and grooving operation. Attention is directed to the fact that the channeling and grooving tool is reciprocally mounted between the toothed wheel 13 and disc 16 and the cutting end thereof is positioned substantially on the vertical meridian of said toothed wheel 13, that is, the channeling and grooving portions of the tool are positioned substantially at the point where the said toothed wheel engages the work. The purpose of this construction is to provide means wherein the said channel and groove will maintain a pre-determined position relative to the edge of the sole throughout the entire grooving and channeling operation. This position is determined by a hook shaped guide member 18 which is supported adjacent the cutting tool 6. A rotary table member 19 is mounted beneath the feed roll 13 to provide means for supporting the edge of the sole as it is fed into the cutting tool 6. The table member 19 is rotatably mounted on a slide rod 20 which is slidably and rotatably mounted in a slide bearing 21 on an arm 22 to provide means by which the table member 19 can be adjusted to desired position relative to the feed roll 13 and cutting tool 6. The table member 19 is rotatably mounted in the slide support 20 by means of roller bearings 33. The arm 22 is provided with a bifurcated portion 23 which is pivoted at 24 to the U shaped portion 2 to provide means by which the table member 19 can be swung towards and away from the feed roll 3 and cutting tool 6. A spring member 25 mounted in the hollow base 1 is adapted to constantly urge the table member 19 towards the said feed roll 3 during the operation of the machine. The hook shaped guide member 18 is adjustably secured to the slide bearing 21 as shown in Figs. III and V, the adjustment being accomplished by simply loosening the lock screws 26 and moving the guide member 18 longitudinally of the slide bearing 21 towards and away from the feed roll 13. This hook shaped guide member is mounted above the table member 19 as shown in Figs. I, II, III and V and is adapted to engage the edge of the sole as the said sole is fed into the cutting tool 6. This provides definite means for controlling the position at which the channel and groove are cut relative to the edge of the sole. The compression of the spring member 25 is varied by tightening and loosening the compression screw 27. The slide support 20 is locked in adjusted position in the slide bearing 21 by means of a clamp screw 28 which is adapted to clamp the said slide rod and firmly hold it in adjusted position. A cam lever 29 is pivoted at 30 to the slide bearing 21 to provide means for holding the rotary table 19 in a depressed position against the action of the spring member 25. This permits the sole material to be placed between the toothed wheel 13 and the edge of the rotary table 19 so that it can be moved, upon rotation of said toothed wheel, into the cutting tool 6. The amount of movement of the table member 19 towards the toothed wheel 13 is controlled by an adjustable screw member 31 which engages with the arm 22 and acts as a stop for controlling the upward movement of said table member. The cutter member 6 as previously described is slidably mounted in the vertical bearing 5 and is adapted to be urged towards the table member 19 by the spring member 8. The limit of the downward movement of the cutter member 6 is controlled by the check nuts 32 which are mounted on the upper threaded end of the cutter support. This provides means for controlling the depth of the cut during the channeling and grooving operation. The cutting tool 6 is angled upwardly from the cutting edge 9 to provide means wherein the said cutting edge will automatically feed into the work at the start of the channeling and grooving operation. This angled portion also causes the lip 17 to move upwardly within the grooved edge of the disc 16. The operation of the device is as follows: The cutter member 6 is first adjusted to desired position relative to the edge of the feed roll 13 by loosening and tightening the check nuts 32. The guide member 18 is then adjusted to desired position relative to the edge of the table member 19 by loosening and tightening the screw members 26. The cam lever 29 is then operated to lower the table member 19 to a position where in the edge of the sole may be placed between the edge of the table 19 and the feed roll 13 as shown in Fig. XVIII. The cam lever 29 is then operated to permit the table to be urged towards the feed roll 13 by the spring member 25. When the work is in position between the table 19 and feed roll 13 prior to the starting of the channeling and grooving operation the cutting tool 6 is held upwardly by the work against the action of the spring member 8. This is caused by the cutter member sliding upwardly in the vertical bearing 5. The handwheel 15 is then rotated to cause the feed roll 13 to rotate and feed the work into the cutter 6. As the work is fed into the said cutter the spring 8 and angled portion of the cutter function simultaneously to cause the said cutter to move into the work. The depth to which this cutter member enters the

work is controlled by the lock nuts 32. The sole is held in engagement with the hook shaped guide member 18 by the hand of the operator as the said handwheel 15 is rotated. In this manner 5 the channel is formed completely around the sole of the shoe adjacent the peripheral edge thereof and is cut to a predetermined depth. The position of the hook shaped end of the guide member 18 with respect to the cutter member 6 controls the position of the cut relative to the peripheral edge of the work.

Attention is directed to the fact that the sole is first mounted and fitted upon the shoe prior to the channeling and grooving operation and the 15 channel and groove are formed adjacent the edge thereof when it is in its fitted position on the shoe. The sole is then sewed in position on the shoe by stitching in the groove 12 after which the lip portion 17 is cemented over the stitches 20 as shown in Fig. XVII. As shown diagrammatically in Fig. XIX a groove may be formed in the said sole separately of the channel or the channel may be formed without the groove as shown 25 in Fig. XX. This is accomplished by tilting the cutter member 6 as shown diagrammatically in these figures or by tilting the table member 19 if desired. In instances where it is desired to 30 tilt the cutter member the said cutter member will be mounted to rotate about the cutting end as the center of the pivot.

The sole channeling and grooving tool 6 as shown in Figs. VI, VII and VIII is formed from sheet material which is blanked out to form the main body portion 40. The body portion is reduced at one end and is bent to form the cutter portion 41. The cutter portion is formed with a sharp edge 42 and is angled upwardly along the line A—A from said edge to provide means for lifting the lip 17 which is formed on the sole 35 during the channeling and grooving operation. This upwardly angled portion is depressed centrally at 43 to form the hollow grooving cutter 11. The said grooving cutter is provided with a sharp edge 44 which normally extends below the sharp edge 42 and is adapted to form a groove in the bottom of the channel. The channel and groove forming cutters are adapted to work in unison and perform both operations simultaneously. The body portion 40 is formed with a recess 45 adjacent one end and a recess 46 intermediate its ends to provide means by which it 40 can be interchangeably secured in operative position on the machine.

The sole channeling and grooving tool shown 55 in Figs. X, XI and XII is formed in a similar manner to that shown in Figs. VI, VII and VIII with the exception of the grooving cutter 11. In this instance the grooving cutter is formed by drilling a hole 47 in the angled portion and 60 sharpening the edge 48.

During the forming of the groove the material which is cut from the sole passes through the opening 47.

From the foregoing description it will be seen 65 that I have provided simple, efficient and economical means for carrying out all of the objects of the invention and that I have provided ready and facile means and method wherein the said channeling and grooving operations may be performed simultaneously or independently of each 70 other.

Having described my invention I claim:

1. In a device of the character described, a feed roll, a lip shaping roll having a grooved peripheral edge adjacent the feed roll and cutter 75

means reciprocally mounted for free sliding and floating spring pressed movement between said rolls.

2. In a device of the character described, a main support, a feed roll rotatably mounted on said support, a rotatable table pivotally mounted on the main support beneath the feed roll, the said table being rotatable in a direction substantially normal to the direction of rotation of the feed roll, a bearing support on the main support and a cutter member reciprocally mounted for free sliding movement in the bearing and having its cutting edge positioned substantially on the vertical center line of the feed roll and adjacent its peripheral edge and coil spring 15 means associated with the cutter member for urging it in the direction of the table.

3. In a device of the character described, a main support, a feed roll and shaping roll rotatably mounted on said main support, a rotatable table pivotally mounted on the main support beneath the rolls, the said table being rotatable in a direction substantially normal to the direction of rotation of the feed roll, a bearing support on the main support in substantial alignment with the vertical axis of the feed roll and a cutter member reciprocally mounted in the bearing and having its cutting edge positioned between the rolls and substantially on the vertical meridian of said rolls and adjacent a peripheral edge thereof.

4. In a device of the character described, a main support, a feed roll and shaping roll rotatably mounted on said support, a rotatable table pivotally mounted on the main support beneath the feed roll and shaping roll for swinging movement towards and away from said rolls and for rotary movement in a direction substantially normal to the direction of rotation of the feed roll, resilient means between the main support and rotatable table for resiliently urging the said table towards the rolls, a bearing support on the main support above the rolls, a cutter member reciprocally supported for free floating movement in said bearing, resilient means on the cutter member for resiliently urging it towards the table, said cutter member being slideable in the bearing and having its cutting edge mounted between the feed roll and shaping roll substantially on the vertical meridian of said rolls and means 40 for rotating the feed roll to feed the work into the cutter.

5. A sole channeling and grooving tool having a relatively straight main body portion formed with an opening adjacent one end, a longitudinal slot intermediate its ends and an angularly extending portion adjacent its opposite end, said angularly extending portion having a sharp edge lying in a plane substantially normal to the plane of the main body portion and having a hollow portion formed with a sharp edge extending below said normally extending sharp edge.

6. In a device of the character described, a sole channeling and grooving tool slidably mounted for free floating reciprocal movement between a feed roll and shaping roll and means associated with the tool for urging it into work fed by said feed roll in a direction transversely of said tool.

7. In a device of the character described a sole channeling and grooving tool slidably mounted for free floating reciprocal movement between a feed roll and shaping roll.

8. In a device of the character described, a main support, a feed roll and shaping roll pivotally mounted in spaced relation on said sup-

port, a tool support having a longitudinal opening therein and a cutting tool adjacent one end thereof, said tool being slidably mounted in the main support for free reciprocal movement between the feed roll and the shaping roll and with the pivot support for said rolls extending through the opening in the tool support.

9. In a device of the character described the combination of a main support having a slideway therein, a feed roll and a spaced shaping roll pivotally mounted on a single pivot member on said support adjacent the slideway, said pivot member lying substantially in line with the longitudinal axis of the slideway, a cutting tool having a longitudinal slot therein mounted for free movement on the pivot member between the feed roll and shaping roll and having a reduced extension slidably mounted in the slideway, a supporting rotatable table member communicating with the feed roll and shaping roll and being adapted to cooperate with the feed roll to feed work into the cutting tool, and means for urging the tool in a direction longitudinally of the slideway towards the table member.

10. In a device of the character described the combination of a main support having a slideway therein, a feed roll and a spaced shaping roll pivotally mounted on a single pivot member on said support adjacent the slideway, said pivot member lying substantially in line with the longitudinal axis of the slideway, a cutting tool having a longitudinal slot therein mounted for free movement on the pivot member between the feed roll and shaping roll and having a reduced extension slidably mounted in the slideway, a supporting rotatable table member communicating with the feed roll and shaping roll and being adapted to cooperate with the feed roll to feed work into the cutting tool, and means for urging the tool in a direction longitudinally of the slideway towards the table member.

11. In a device of the character described the combination of a main support having a slideway therein, a feed roll and a spaced shaping roll pivotally mounted on a single pivot member on said support adjacent the slideway, said pivot member lying substantially in line with the longitudinal axis of the slideway, a cutting tool

having a longitudinal slot therein mounted for free movement on the pivot member between the feed roll and shaping roll and having a reduced extension slidably mounted in the slideway, a supporting rotatable table member communicating with the feed roll and shaping roll and being adapted to cooperate with the feed roll to feed work into the cutting tool, means for urging the tool in a direction longitudinally of the slideway towards the table member, and a guide member 10 overlying the table member adjacent the feed roll.

12. In a device of the character described, a main support, an upper and lower feed roll on said support, said upper feed roll being mounted 15 to rotate and to be held in a fixed position on said support and the lower feed roll being mounted to move toward and away from the upper feed roll and a cutting tool mounted on said support for free reciprocal straight line movement 20 in a direction substantially parallel with the vertical meridian of the upper feed roll and substantially along said vertical meridian and means for urging the cutting tool toward the lower feed roll.

13. A sole channeling and grooving tool having a relatively straight main body portion formed with connecting means adjacent one end, a longitudinal slot intermediate its ends and an angularly extending portion adjacent its opposite 30 end, said angularly extending portion having a sharp edge lying in a plane substantially normal to the plane of the main body portion and having a depending lip portion adjacent said sharp edge, said depending lip having a sharp 35 edge spaced from the sharp edge of the angularly extending portion.

14. In a device of the character described, a main support, upper and lower feed rolls on said support, said feed rolls being mounted to rotate 40 and one of said rolls being movable towards and away from the other, and a cutting tool mounted on said support for free reciprocal movement in a direction substantially parallel with the vertical meridian of the upper feed roll and substantially along said vertical meridian and means for urging the cutting tool towards the lower feed roll.

GEDEON GREGOIRE.
